United States Patent Office.

GEORGE FAUL, OF BOSTON, MASSACHUSETTS, ASSIGNOR TO SAMUEL F. HILTON, OF PROVIDENCE, RHODE ISLAND.

Design No. 4,471, dated November 15, 1870.

DESIGN FOR A BOX FOR PUTTING UP PAPER CUFFS.

The Schedule referred to in these Letters Patent and making part of the same.

I, GEORGE FAUL, of Boston, in the county of Suffolk and State of Massachusetts, have invented and produced a new and original Design for a Box to be used as a Merchantable Package for Putting up Paper Cuffs and for other purposes, of which the following is a specification.

The nature of my design is fully represented in the accompanying drawings, to which reference is made, and consists of a box embodied in the form of a bottle, the same being divided in two parts as at the line D, the upper part A being the cover of the said box, and may be turned in form from wood, and the lower

part, B, being the box, which may be made of pasteboard or wooden splint, and the whole covered with colored paper, and with labels or devices in furtherance of such design.

Claim.

I claim as my invention—
The design for a box, as set forth.

GEORGE FAUL.
